CLAIM

What is claimed is the ornamental design for a tag, as shown and described.

DESCRIPTION

FIG. 1 is a perspective view of a tag, showing the new design; FIG. 2 is a front elevational view thereof; FIG. 3 is a rear elevational view thereof; FIG. 4 is a top plan view thereof, the bottom plan view being a mirror image thereof; and, FIG. 5 is a left-side elevational view thereof, the right-side elevational view being a mirror image thereof. The broken lines showing a textual phrase in FIG. 1 is included for the purpose of illustrating the invention in use, and form no part of the claimed design.
